BOBBIN SUPPORT FOR WEFT REPLENISHING LOOMS

Richard G. Turner, Worcester, Mass., assignor to
Crompton & Knowles Loom Works, Worcester,
Mass., a corporation of Massachusetts

Application March 8, 1943, Serial No. 478,328

8 Claims. (Cl. 139—247)

This invention relates to improvements in weft replenishing looms and it is the general object of the invention to provide yieldable bobbin supports so constructed as to prevent breakage or abrasion of the weft end extending from the bobbin being transferred.

Weft replenishing looms operate with a group of reserve bobbins transferred one by one into the depleted shuttle. In order that the shuttle may be threaded it is necessary to hold the weft end of the incoming bobbin during the flight of the shuttle subsequent to replenishment. This weft end customarily leads from the bobbin over and along yielding bobbin supports to a thread holder and at the time of transfer there is danger that this weft end will be pinched or broken as it is forced downwardly between the bobbin tip and the bobbin support.

It is an important object of my present invention to provide the bobbin support with a roller positioned for engagement with the bobbin tip and mounted to turn during downward movement of the bobbin during transfer for the purpose of preventing the bobbin support from rubbing or abrading the weft end.

As bobbins await transfer in the magazine they have a tendency to turn on their axes due to loom vibration. When a pneumatic thread holder such as shown in my prior Patent No. 2,262,308 is used, the weft ends are likely to be drawn by pneumatic attraction into a notch defined by the bobbin tip and the yielding support with likelihood that the end will be dragged along the thread holder and injured. It is a further object of my present invention to provide a yielding bobbin support with a roller or the like to engage the bobbin tip and turn as the bobbin turns to avoid damage to the thread in the notch.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a front elevation of a weft bobbin magazine and thread holder of a type with which my invention can be used.

Fig. 2 is an enlarged vertical section on line 2—2 of Fig. 1 looking from the center of the magazine toward the thread holder and showing my invention applied to the bobbin tip supports, with the magazine in position to transfer from the front or right hand stack of bobbins.

Fig. 3 is a view similar to the lower end of Fig. 2 setting forth the relation between the lowest bobbins in the stacks and their respective tip supports before a transferring operation is started.

Fig. 4 is a view similar to a portion of Fig. 3, but showing the lowest bobbin in the left hand or rear stack moving downwardly during transfer, and

Fig. 5 is a detailed plan view looking in the direction of arrow 5, Figure 3.

Referring to the drawing, the magazine M is shown in Fig. 1 as provided with inner and outer plates 10 and 11, respectively, between which extend two stacks of reserve bobbins B, the front and back stacks being designated generally at F and R. The butt ends 12 of the bobbins are guided in grooves 13 formed in the inner plate 10, while the outer plate has grooves 14 to guide the tips 15 of the bobbins in the front and rear stacks, respectively.

The outer plate 11 is provided with a stud 20 on which are pivoted front and back bobbin tip supports 21 and 22, respectively. Support 22 has an extension 23 carrying an adjustable stop screw 24 positioned for engagement with a lug 25 which may be formed integral with the outside plate 11. A compression spring 26 is located between the two supports 21 and 22 and acts normally to hold them apart. An extension 27 of the lug 25 engages the front support 21 to limit forward movement thereof under action of the spring 26, and the latter normally holds the stop screw against the lug. Each support is capable of movement toward the other when a bobbin is transferred from the corresponding stack. The support 21 positions the lowest bobbin in the front stack F for transfer, while the back support 22 performs a similar function for the lowest bobbin in the rear stack R.

Secured on the inside of the outer plate 11 is a forward guide wire 30 which is inclined downwardly and away from plate 11 as shown in Fig. 1, and around which extend the weft ends W of the front stack of bobbins. A second wire 31 is also secured on the inside of the outer plate 11 and passes downwardly between the two stacks of bobbins and has a curved lower end 33 as shown in Fig. 2. The weft ends W' of the rear stack extend from the conical parts of the rear bobbins around the wire 31 and then outwardly toward a thread holder H which may operate pneumatically to tension the weft ends and be constructed as in my prior Patent No. 2,199,353.

Except as noted hereinafter the mechanism thus far described is constructed and operated in the usual manner as set forth in the aforesaid patents. The magazine is mounted to rock about the pivot 35 so that the lowest bobbin in either the front or the back stack can be in transferring position with respect to the shuttle S. As shown in Fig. 2 the front stack is positioned for transfer but it is to be understood that the magazine can move angularly in a left hand direction as viewed in Fig. 2 to place the lowest bobbin in the rear stack in transfer position. The transerrer arm T descends in the usual manner to move the bobbin under it into the shuttle S, at which time the weft end of the bobbin being transferred descends with the latter while remaining attached to the thread holder H.

When fine wefts are used there is likelihood that the weft ends W and W' will be scraped along the bobbin support when the latter are constructed as shown in the aforesaid Patent No. 2,262,380, and it is the general purpose of my present invention to prevent this scraping by mounting rollers or the like on the supports in position for engagement with the tip of the bobbin being transferred and the weft end of the latter.

Accordingly, the support 22 is provided with ears 40 and 41 through which extend a guide pin 42 on which is mounted a roll 43 which extends beyond the outline of the support 22, as shown in Fig. 3. The latter may be made of any appropriate material, such as a plastic composition, and preferably has the sides thereof curved as shown more clearly in Fig. 5. The roll is so located as to engage the tip of the lowest bobbin in the rear stack and assist in holding the latter in transfer position. The weft end W' of the bobbin which engages the roll extends from the conical part C of its bobbin toward the center of the magazine, around one side of the wire 31 and then outwardly in front of the wire, and then along the bobbin tip to the thread holder. The latter exerts tension on the weft end and tends to draw it to the position shown in Fig. 5, that is, into the notch between the bobbin tip and the roll 43 above the point of contact between the roll and the bobbin tip. If there is any rotation of the bobbin due to vibration of the loom the roll can rotate on its axis and may under these conditions engage the weft end but will not abrade the latter because of the fact that the bobbin and roll have rolling contact with each other and the weft end is therefore not subjected to scraping or injurious distortion.

During transfer when the magazine is in position to place the lowest bobbin in stack R in transfer position, the bobbin will move down as indicated by arrow a Fig. 4 under action of the transerrer arm T and will cause movement of the support 22 to the right as viewed in Fig. 2 against the action of spring 26. The roll will turn and the thread can therefore pass from its normally raised position downwardly between rolling surfaces as the bobbin moves into the shuttle S without being subject to a sliding or scraping action on the part of the bobbin tip support.

The location of the weft end of the bottom rear bobbin will depend somewhat upon the point from which it leaves the conical part of its bobbin. If the thread leaves the under part of the cone on the bobbin it will be led upwardly around the wire 31 and thence over the roll to the thread holder and be subjected to an appreciable down-

ward force by the pneumatic attraction of the holder. If, on the other hand, the thread leads from the upper part of the conical end of the weft mass on the bobbin there will be less downward force exerted on the weft end but it will nevertheless be in position to fall into the notch between the bobbin tip and the roll 43 during transfer. In any event, the weft end will be tensioned by the thread holder and will lie in the aforesaid notch.

The front support 21 is shown in Figs. 2 and 3 as provided with a roll 50 similar in construction and mounting to the roll 43. This roll 50 is not positioned to engage the weft end of the lowest bobbin in the front stack F when the magazine has the specific construction illustrated herein. Roll 50 will turn, however, to prevent scraping of the bobbin tip, and this last feature is also true with respect to roll 43. Rolls are used on both of the supports for the sake of uniformity.

From the foregoing it will be seen that I have provided simple means for preventing abrasion of the weft thread during transfer by providing a rolling surface on the bobbin tip support so placed that the weft end passes downwardly without being abraded. It will also be seen that the roll is so placed as to lie normally under a weft end which extends from the bobbin around the guide wire 31 and thence to the pneumatic thread holder.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a bobbin in transfer position provided with a mass of weft from which a weft end extends along the tip of the bobbin to a thread holder, a support for the bobbin tip, resilient means to hold the support toward the bobbin tip, and a roller carried by the support to engage the bobbin tip at a point below said weft end, the bobbin when transferred downwardly causing rotation of the roller and movement of the weft end between said roller and bobbin tip.
2. In a weft replenishing loom having a bobbin in transfer position provided with a mass of weft from which a weft end extends along the tip of the bobbin tip to a thread holder, a bobbin tip support pivotally mounted with respect to the loom, resilient means urging the support toward the bobbin tip, and a roller located and mounted on the support in position to engage the bobbin tip at a point under the weft end, said bobbin when moving downwardly causing the thread to pass between the bobbin tip and the roller and causing the latter to rotate.
3. In a weft replenishing loom having a bobbin in transfer position provided with a mass of weft from which a weft end extends along the tip of the bobbin to a thread holder, a bobbin tip support, resilient means urging the support toward the bobbin tip, a roller rotatably mounted on the support and held against the bobbin tip by said resilient means, and means to guide the weft end along a path between the bobbin tip and the roll toward the thread holder, the bobbin upon downward motion thereof causing the weft end to pass between the tip and the roller and causing rotation of the latter.
4. In a weft replenishing loom having a bobbin in transfer position provided with a mass of weft from which a weft end extends along

the tip of the bobbin to a thread holder, a bobbin tip support, resilient means urging the support toward said bobbin tip, a roller located and mounted on said support and held by said resilient means in engagement with the bobbin tip, the latter and the roller forming a notch, and means to guide the weft end along a path extending through said notch toward the thread holder, the bobbin upon downward motion thereof causing the weft end to move downwardly between the bobbin tip and the roller and causing rotation of the latter.

5. In a weft replenishing loom having a reserve bobbin which tends to rotate on its axis and from which a weft end is drawn along the tip of the bobbin by a thread holder, a bobbin tip support, resilient means urging the bobbin support toward the tip of the bobbin, and a roller rotatably mounted on the support and held against the bobbin tip by said resilient means and defining with said bobbin tip a notch in which said weft end is drawn by the thread holder, said roller turning on the axis thereof when the bobbin turns due to engagement with

the latter, whereby the thread when drawn into said notch by the combined action of the thread holder and the turning of the bobbin will engage the rotation surfaces of said bobbin tip and roller.

5. A bobbin tip support for a weft replenishing loom, said support having provision for pivotal mounting, and a roller rotatably mounted on said support for engagement with the bobbin tip.

10. A bobbin tip support for a weft replenishing loom, said support having provision for pivotal mounting, and a roller rotatably mounted on said support for engagement with the bobbin tip and the bobbin tip engaging surface of which extends beyond the outline of said support.

15. 8. In a bobbin tip support for a weft replenishing loom, said support having provision for pivotal mounting, an arm forming part of said support and carrying a stop screw, and a 20 second arm forming a part of said support, and a bobbin tip engaging roller rotatably mounted on said second arm.

RICHARD G. TURNER.
